OTHER PUBLICATIONS

Written Opinion and International Search Report dated Aug. 28, 2019 for PCT/IL2019/050502 filed May 5, 2019.

Primary Examiner — Cynthia Ramirez*(74) Attorney, Agent, or Firm* — Connie R. Masters(57) **CLAIM**

The ornamental design for a vacuum gripper, as shown and described.

DESCRIPTION

FIG. 1 is a perspective top view of a vacuum gripper, showing my new design;

FIG. 2 is a perspective bottom view thereof;

FIG. 3 is a rear view thereof;

FIG. 4 is a front view thereof;

FIG. 5 is a left side view thereof;

FIG. 6 is a right side view thereof;

FIG. 7 is a top view thereof;

FIG. 8 is a bottom view thereof; and,

FIG. 9 is a sectional view thereof, taken along line 9-9 of FIG. 2.

The broken lines in the figures show portions of the vacuum gripper, which form no part of the claimed design.
